(57) **CLAIM**

The ornamental surface ornamentation for a panel in particular an engineered wood panel, as shown and described.

DESCRIPTION

The patent or application file contains at least one drawing executed in color. Copies of this patent or patent application

publication with color drawing(s) will be provided by the Office upon request and payment of the necessary fee.

1.-89. Surface ornamentation for a panel, in particular, an engineered wood panel

FIG. 1.1 is a top plan view of a first embodiment of a surface ornamentation for a panel in particular an engineered wood panel showing my new design;

FIG. 2.1 is a top plan view of another embodiment of a surface ornamentation for a panel in particular an engineered wood panel showing my new design;

FIG. 3.1 is a top plan view of another embodiment of a surface ornamentation for a panel in particular an engineered wood panel showing my new design;

FIG. 4.1 is a top plan view of another embodiment of a surface ornamentation for a panel in particular an engineered wood panel showing my new design;

FIG. 5.1 is a top plan view of another embodiment of a surface ornamentation for a panel in particular an engineered wood panel showing my new design;

FIG. 6.1 is a top plan view of another embodiment of a surface ornamentation for a panel in particular an engineered wood panel showing my new design;

FIG. 7.1 is a top plan view of another embodiment of a surface ornamentation for a panel in particular an engineered wood panel showing my new design;

FIG. 8.1 is a top plan view of another embodiment of a surface ornamentation for a panel in particular an engineered wood panel showing my new design;

FIG. 9.1 is a top plan view of another embodiment of a surface ornamentation for a panel in particular an engineered wood panel showing my new design;

FIG. 10.1 is a top plan view of another embodiment of a surface ornamentation for a panel in particular an engineered wood panel showing my new design;

FIG. 11.1 is a top plan view of another embodiment of a surface ornamentation for a panel in particular an engineered wood panel showing my new design;

FIG. 12.1 is a top plan view of another embodiment of a surface ornamentation for a panel in particular an engineered wood panel showing my new design;

FIG. 13.1 is a top plan view of another embodiment of a surface ornamentation for a panel in particular an engineered wood panel showing my new design;

(Continued)

FIG. 53.1 is a top plan view of another embodiment of a surface ornamentation for a panel in particular an engineered wood panel showing my new design;

FIG. 54.1 is a top plan view of another embodiment of a surface ornamentation for a panel in particular an engineered wood panel showing my new design;

FIG. 55.1 is a top plan view of another embodiment of a surface ornamentation for a panel in particular an engineered wood panel showing my new design;

FIG. 56.1 is a top plan view of another embodiment of a surface ornamentation for a panel in particular an engineered wood panel showing my new design;

FIG. 57.1 is a top plan view of another embodiment of a surface ornamentation for a panel in particular an engineered wood panel showing my new design;

FIG. 58.1 is a top plan view of another embodiment of a surface ornamentation for a panel in particular an engineered wood panel showing my new design; and

FIG. 59.1 is a top plan view of another embodiment of a surface ornamentation for a panel in particular an engineered wood panel showing my new design.
